UNITED STATES PATENT OFFICE.

WILLIAM KANE, OF PHILADELPHIA, PENNSYLVANIA.

AUTOMATIC GAS-REGULATOR.

1,361,336.

Specification of Letters Patent.

Patented Dec. 7, 1920.

Application filed November 19, 1919. Serial No. 339,160.

To all whom it may concern:

Be it known that I, WILLIAM KANE, a citizen of the United States, residing at Philadelphia, in the county of Philadelphia and State of Pennsylvania, have invented 5 certain new and useful Improvements in Automatic Gas-Regulators, of which the following is a specification.

One object of my invention is to provide 10 an improved device which automatically operates to vary the supply of gas fuel to a burner so that the burner will supply a desired amount of fuel to suit various requirements. For example my invention can be 15 used advantageously in connection with a steam generating apparatus for vulcanizing or other purposes where it is necessary to maintain a uniform pressure of steam and when so used will automatically operate 20 through the medium of the steam generated to regulate the amount of gas fuel to keep the steam at a desired uniform pressure.

Another object is to so construct my invention that it can be used without material 25 change for connection to apparatus of various sizes since gas pipes of different diameters can be easily attached thereto and it will operate in connection with large apparatus as well as in connection with small 30 apparatus.

Another object is to make the parts of my invention in such manner that they can be easily made, put together, and taken apart.

A further object is to make my invention 35 of a simple construction and so that it can be easily regulated to suit numerous requirements.

These objects, and other advantageous 40 ends which will be described hereinafter, I attain in the following manner, reference being had to the accompanying drawings in which—

Figure 1 is a central vertical sectional 45 elevation of my improved regulator, and Fig. 2 is a transverse sectional view taken on the line 2—2 of Fig. 1.

Referring to the drawing, 3 represents a 50 hollow base section closed at its bottom and sides and open at its top. This section is preferably made comparatively large and substantially square in cross section, one of the sides 4 is preferably thickened and as illustrated this thickening of the side is produced by providing a boss 5 which extends 55 substantially throughout the height and width of the section to permit tapped open-

ings, such as the opening 6 to be provided so that an inlet gas pipe 6^a of any diameter can be connected thereto to supply gas to the chamber 7 within said base section. The 60 upper portion of the base section is provided with a flange 8 which forms a seat for a hollow top section 9; said top section having an outwardly projecting flange 10 which rests upon the flange 8 and is secured thereto by 65 bolts 11. The top section 9 has an inwardly projecting flange or partition 12 which has a central aperture 13 which is made comparatively large, as clearly illustrated in Fig. 2.

Three pins 14 have their upper ends screw 70 threaded, as shown at 15, and are adapted to be screwed into tapped holes in the partition 12. The portions 16 of the pins 14 between the heads 17 and the screw threaded 75 parts 15 are made smooth and extend through holes in a disk valve 18; said disk valve being of larger diameter than the aperture 13. The heads 17 of the pins 14 are larger than the holes in the disk valve 18 80 and serve to normally support the disk valve in a position away from the partition 12, as shown in Fig. 1. However, it will be noted that the disk valve is free to slide upwardly 85 on the pins 14 as guides and if raised from the position shown in Fig. 1 would tend to vary the amount of gas passing from the chamber 7 into the chamber 19 provided by the top section 9.

A tube 20 has a screw threaded nipple extension 21 which fits within the bottom 22 of the base section 3 and extends below said bottom 22. This nipple extension permits the attachment of a steam pipe (not illustrated) which, for example, may lead from 95 a steam boiler or generator for the purpose of supplying steam to a vulcanizing apparatus or other apparatus to which it is desired to supply steam at a uniform pressure.

A lever 23 has one end pivotally connected at 24 to a plug 25^a which may be screwed into the side of the base section and this lever normally extends over the top of an arcuate portion 25 of the tube 20. A free end 26 of the lever 23 is positioned directly below the 100 middle of the disk valve 18.

The side 27 of the top section 9 is thickened in a manner similar to the side 4 of the bottom or base section 3 by providing a boss 28; said boss being of comparatively 110 large diameter to permit a tapped opening such as 29 to be formed therein for the at-

tachment of an outlet gas pipe 29^a which may lead to a burner or burners of the steam boiler or generator above mentioned. It will be noted that by providing the comparatively large boss 28 that outlet gas pipes of various diameters can be readily attached thereto. An adjusting rod 30 has a screw threaded portion 31 which fits within a tapped hole 32 in the extreme top of the section 9 and has a stem 33 which depends through the aperture 13, as clearly shown in Fig. 1. The upper end of this adjusting rod is provided with a knob 34 whereby it can be turned to vary the position of the bottom end of the stem 33 relatively to the bottom of the partition 12.

The adjusting rod 30 can be moved so as to extend various distances below the plane of the bottom of the partition 12 and when thus positioned, the disk valve 18 can only be raised until it strikes the bottom of said adjusting rod 30. By this means, as will hereinafter be described, the device can be made to operate so that the disk valve can be limited in its upward or closing movement to suit various requirements.

In the operation of my device, considering that the pipe 29^a is supplying gas to a burner for generating steam and that a portion of said steam is conveyed to said tube 20 by means of a pipe (not illustrated) which is connected to the nipple extension 21, when the steam attempts to increase beyond a certain predetermined pressure, the free arcuate end portion 25 of the tube 20 will tend to straighten out and in so doing will engage the lever 23 between the pivot 24 and the end 26 and move said end 26 into engagement with the disk valve 18 and thereby raise the disk valve on the pins 14 as guides toward the aperture 13. This will cut off a portion of the gas supply passing through the aperture 13 and consequently reduce the amount of gas passing to the burner through the pipe 29^a. The flame of the burner will then be reduced and the pressure of the steam will consequently be reduced. When the steam is thus reduced in pressure, the arcuate portion 25 of the tube 20 will again move toward its normal arcuate position to permit the lever 23 to lower and the disk valve 18 will consequently drop to permit more gas to be supplied to the pipe 29^a. In this manner the steam is kept at a uniform pressure. By having the lower end of the adjusting rod 30 extending below the plane of the bottom of the partition 12, it is impossible for the disk valve 18 to entirely close the aperture 13 so that the burner will never be entirely extinguished. Thus it is unnecessary to provide any additional bypasses from the gas to the burner since the amount of constant supply can be varied by adjusting the vertical position of the rod 30. Thus the amount of fuel desired will be sup-

plied automatically so as to suit the change in demands for steam made upon the boiler.

To take the device apart it is merely necessary to remove the bolts 11 and the entire top section with the disk valve thereon can be removed and by inverting the top section, the pins 14 can be quickly unscrewed from the partition 12 after which the pins can be easily removed from the valve. Furthermore, after the top section 9 is removed, it is an easy matter to remove the arcuate tube 20 by swinging the lever 23 upwardly and then unscrewing the tube 20, after which the entire lever and plug 29^a can be removed. It will be further understood that by interposing the lever 23, a mechanical advantage is attained since a very small movement of arcuate portion 25 of the tube 20 will impart a comparatively great movement to the end 26 of the lever 23.

The parts of my invention can be easily assembled and the pins 14 provide smooth guides and prevent the disk valve 18 from jamming or becoming distorted in any manner.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A gas regulating device including a hollow base section; a hollow top section mounted above said base section, said sections respectively having openings therein providing gas inlet and outlet passages, there being a communicating aperture between said sections whereby gas can pass into one of said sections through its inlet passage then through said aperture into the other section and out through its outlet passage; guiding members depending from one of said sections into the space within said base section; a valve slidably connected to said members; a pressure tube containing pressure fluid and having a portion movable due to variation of pressure of said fluid established therein; and a lever interposed between said portion of the pressure tube and the valve whereby the valve is moved toward said aperture due to the movement of said portion of the pressure tube through the medium of said lever; substantially as described.

2. A gas regulating device including a hollow base section; a hollow top section mounted above said base section, said sections respectively having openings therein providing gas inlet and outlet passages,

- there being a communicating aperture between said sections, whereby gas can pass into one of said sections through its inlet passage then through said aperture into the other section and out through its outlet passage; guiding members depending into said base section; a valve slidably connected to said members; and a pressure tube containing pressure fluid and having a portion movable due to variation of pressure of said fluid established therein, said portion of the tube being operative to effect the raising of said valve on said guide members toward said aperture; substantially as described. 45
- 5 3. A gas regulating device including a hollow base section; a hollow top section positioned above said base section, said sections respectively having openings therein providing gas inlet and outlet passages, there being a communicating aperture between said sections whereby gas can pass into one of said sections through its inlet passage then through said aperture into the other section and out through its outlet passage; guiding means connected to one of 50 said sections and depending into said base section; a valve slidably connected to said means so as to move axially with respect to said aperture; and a pressure tube containing pressure fluid and having a portion 55 movable due to variation of pressure of said fluid established therein, said portion of the tube being operative to effect the raising of said valve on said guiding means toward said aperture; substantially as described. 60
- 10 4. A gas regulating device including a hollow base section; a hollow top section positioned above said base section, said sections respectively having openings therein providing gas inlet and outlet passages, there being a communicating aperture between said sections whereby gas can pass into one of said sections through its inlet passage and then through said aperture into the other section and out through its outlet 65 passage; guiding members depending from one of said sections into the space within said base section; a valve slidably connected to said members; a pressure tube containing fluid and having a portion movable due to variation of said fluid pressure established therein, said portion of the tube being operative to effect the raising of said valve on said guide members toward said aperture; and an adjusting rod having a portion movable into a position to be engaged by said valve during its upward movement and thereby prevent the entire closing of said aperture by the valve; substantially as described. 70
- 15 5. A device of the character described including a casing having two chambers, one mounted above the other and being provided with an aperture to permit gas to pass from the lower chamber upwardly therethrough into the upper chamber; vertically positioned guiding members secured to said casing; a valve slidably mounted on said guiding members; means automatically operative to move said valve toward and from 75 said aperture whereby the amount of gas passing therethrough can be automatically controlled; and a rod in screw threaded connection with said casing and adapted for abutment with said valve to vary the distance which said automatic means can move the valve; substantially as described.
- 20 In testimony whereof I have signed my name to this specification in the presence of two subscribing witnesses.
